UNITED STATES PATENT OFFICE

2,012,691

ELECTROLYTIC CONDENSER

Joseph A. Poitras, Fort Lee, N. J., assignor to
Solar Manufacturing Corporation, a corpora-
tion of New York

Application March 26, 1934, Serial No. 717,347

8 Claims. (Cl. 175—315)

My invention relates to electrolytic devices, such as electrolytic condensers, rectifiers or the like, comprising film-forming electrodes. These condensers are based upon the well known principle that when certain metals, as for instance aluminum, tantalum, etc. are used as electrodes and are placed in suitable electrolytes, they are upon application of the proper voltage covered by a film which, as far as conductivity is concerned, is of a uni-directional character. These condensers are used for different purposes, one of their uses being in filter circuits to eliminate the alternating current ripples from rectified currents. However, it should be well understood that my invention is not limited to such purposes and applications.

When electrolytic condensers are used for the above stated purpose, only one of the electrodes, namely, the anode, is required to be of film-forming metal,—preferably aluminum. The cathode which, as a rule also forms the container of the condenser, is usually made of a metal which does not exhibit film-formation, or at least, not to a marked extent, as such film-formation on the cathode always results in a smaller initial capacity and larger power factor than desirable. However, in practice it has been found that for economical reasons, in spite of this drawback, containers of aluminum which serve as cathodes are quite practical, and their shortcomings in the above mentioned respect may be overcome by different means, one of which is, among other advantages, embodied in the improved novel construction, about to be described. Aluminum can be easier subjected to mechanical operations, and electrolytic condensers with an aluminum container, serving as cathode, are far less expensive, and also much lighter than those made with a copper or nickel cathode.

Aside from this incidental feature, i. e., the improved serviceability of an aluminum cathode container, the special improvement and novel features which characterize this invention, are however not concerned with the formation of the aluminum (or any other metal) cathode but with that of the aluminum anode, and moreover they are confined to only one species of electrolytic condensers, namely so-called spiral-wound condensers. The general principle, on which these condensers are built, is as follows: The anode, composed of aluminum or other metal, capable of forming the necessary dielectric film on its surface, is a strip of sheet metal fastened to and wound spirally around a stiff rod of the same metal. This rod usually forms the anode terminal. The turns are spaced apart by different means, usually depending only upon their resiliency and tendency to spread, analogous to the way a watch spring would spread. Sometimes the sheets were perforated by apertures whose

punched out, extruded or burred edges served as eventual spacers between adjacent turns. No special insulating layers or separators were thought necessary, neither between the turns of the spirally wound sheet nor between the whole anode coil and the cathode wall, as the dielectric film of aluminum oxide, formed all over the anode sheet, was supposed to sufficiently insulate adjacent elements from each other. Sometimes a celluloid or cellophane sheet was inserted between the container wall and the anode element. This arrangement has proved in practice deficient in different and opposite directions. A nearly impervious insulating sheet, like cellophane or celluloid, offers too much resistance to the desirable free circulation of the electrolyte solution; on the other hand, if one depends upon the insulating quality of the oxide film alone, it will in the long run not be found very reliable. By accidental contact the film layer is easily rubbed off in places, and a short-circuit path is formed without a chance of repairing the broken film. This changes the surface capacity and the power factor detrimentally, if the short circuit is confined to the turns of the anode alone, but if the inner container surface and the outer peripheral turn of the anode element is short-circuited, the condenser is rendered useless. But even if no actual metallic contact occurs between the outer turn of the anode electrode and the inner surface of the container, unprotected by either an insulating sheet or by plating with another non-filming metal, the aluminum cathode is still liable to quickly deteriorate or corrode. One reason is that when the condenser is used, the alternating current ripples, passing through the condenser, if of sufficient magnitude, have the tendency to gradually build up a film on the cathode too, through electrolytic action of the current flowing at minute intervals in a direction opposed to that of the direct current component of the rectified current. The same thing results from the self-induced countercurrent which occurs whenever the source of current is being switched off. And this film-forming action is advanced by the absence of any impediments in the path of the ionic components. The film thus formed on the cathode represents a capacity which is in series with the capacity of the film on the anode and this series combination of the two capacities reduces the efficiency of the condenser. However, as long as the voltage of the ripples is small, compared with the voltage of the direct current component, the film formation, due to this cause, would not be sufficient to explain the great drop of efficiency which nevertheless often occurs and is accompanied with a considerable oxidation and even corrosion of the inside of the container, and we will have to look for a further cause for this phenomenon.

- It is known that due to electrolytic action during operation, oxygen is liberated from the electrolytic solution, which partly escapes, but is also liable to attack the cathode,—especially during the intervals when a ripple occurs and the polarity is momentarily reversed—by purely chemical action. The oxide film thus formed through purely chemical action of the oxygen is similar to that effected by electrolytic action, but the power factor of such chemically built-up film is much larger (about 100%) than that of an electrolytically formed film of the same thickness, as experiments have proven. This deleterious effect is the more noticeable the nearer the outer anode surface is to the cathode container, and the less impediments there are to prevent an accumulation of gas bubbles on the latter. To eliminate these different drawbacks mentioned is the general purpose of the present invention.
- It is therefore among the objects of this invention to provide means whereby a metallic contact between the inner turns of a spirally-wound anode sheet of an electrolytic condenser is effectively prevented.
- Another object of this invention is to provide means whereby a metallic contact with consequent short-circuit between the outer turn of the anode-spiral and the cathode, representing the container of the electrolyte, is prevented.
- A further object of this invention is to provide insulating means between the separate turns of a spirally-wound condenser or between the outside surface of the anode spiral and the cathode container which do not interfere with the free circulation of the electrolytic liquid.
- A further object of my invention is to provide insulating means, serving the aforesaid purposes which are adapted to intercept the gas bubbles formed during electrolytic action and prevent their accumulation on the cathode electrode.
- Another object of my invention is to arrange the insulating means in such a way that sparking over or loss of capacity by so-called corona-effect between the extreme edges of the anode spiral and the cathode container is minimized.
- Another object of my invention is to provide such construction of the anode electrode, that free circulation of the electrolytic solution is facilitated.
- This circulation, if it were to follow its natural course in an unobstructed cylindrical container with a liquid electrolyte would form an ascending central column of warmer liquor, spreading out radially near the top in mushroom-like fashion and returning toward the center near the bottom.
- Another object is to provide means whereby the free gas bubbles, formed during electrolytic action, are more quickly deprived of their electric charge and consequently will be discharged toward the surface in a neutral non-electric state.
- A further object is to provide supporting means whereby the insulating layers provided between the spiral turns are securely kept in place and their dislocation is prevented.
- Other more specific objects and advantages of my device will appear as the nature of the improvements is better understood, the invention consisting substantially in the novel arrangement and correlation of instrumentalities herein fully described and illustrated in the accompanying drawing wherein similar reference characters are used to describe corresponding parts throughout the several views and then finally pointed out

and specifically defined and indicated in the appended claims.

The disclosure made the basis of exemplifying the present inventive concept suggests a practical embodiment thereof, but the invention is not to be restricted to the exact details of this disclosure, and the latter therefore is to be understood from an illustrative, rather than a restrictive standpoint. It will be also understood that the various features of the present invention disclosed may be separately applicable despite their cooperation herein shown.

In the accompanying drawing—

Fig. 1 is a sectional elevation of an electrolytic condenser, embodying the principles of my invention, showing the anode electrode partly in full. The section is taken along line I—I of Fig. 2.

Fig. 2 is a horizontal cross section through such a condenser, illustrating the manner in which the anode is wound.

Fig. 3 is a similar horizontal cross section illustrating a modification of the winding.

Fig. 4 is a top view, partly sectional of the condenser, showing the venting device.

Fig. 5 is a fragmental sectional view, showing a modification of the venting device.

Fig. 6 shows the terminal connection for the anode electrode.

Fig. 7 is a detail showing how the insulating gauze may be held in place by a corner clip of the aluminum sheet as at "A", Fig. 2.

Fig. 8 is a detail showing how the end of a gauze strip may be clipped to the continuous edge of an aluminum sheet, as at "B", Fig. 3.

Similar characters denote similar parts throughout the different views.

Referring more in detail to the separate views, the container 20 forms the anode electrode and, as already said, may be of aluminum, although it could be made of a non-film-forming, non-corrosive metal, like copper or nickel. The electrolyte 21 is indicated as being liquid.

The outer container 20 can be shaped in different ways, but in the majority of cases it may be formed from a tubular blank, by contracting, pressing or spinning one end over a suitable mandrel into the proper form. The tube is contracted by spinning to a smaller diameter and then drawn out to a tubular neck 28. Over this neck the sleeve 29 is slipped and the protruding end 30 of the container neck is swaged out over the end of the sleeve by a spinning tool to retain the sleeve in place. Through this neck 28 protrudes the terminal 23 of the anode 22 which will be described later, and the space between the tubular neck and the terminal is filled by an insulating substance 31, like rosin or asphalt which hardens, when cooled.

Generally the terminal end of the condenser 60 is supported on a bracket or platform 32 in any suitable manner. If the outside of the sleeve is threaded, a hexagonal nut 33 can be used to clamp the sleeve and thereby the condenser to the platform which is apertured in a suitable manner. A washer 34 and a plate 35, adapted to serve as a binder post for attaching the cathode lead 36 to it, can be inserted around the sleeve 29 where it passes through the aperture in the platform.

The upper end of the container is closed hermetically in the following way: A dished or cupped end member 60 is inserted into the open end of the tubular container 20. The outer flange 60a of this member has an inward inclination so that

the general shape of this cupped member resembles a conical frustum, though only slightly deviating from the cylindrical form. The outer diameter of the bottom is equal to the inside diameter of the tubular member 20 and, after the cupped member 60 is inserted to its proper depth into the assembled container, the outer rim 28 of the container is tightened by spinning it toward the conical wall of the cupped member 60. At the same time the upper rim 60b is spun outwardly and crimped over the contracted rim 28 so as to form a tightly interlocking joint with the latter.

The middle portion of the cupped member 60 is raised to form a cylindrical head 61 which has a central larger opening and one or more small perforations 62 through which gas under pressure can escape. The gas holes are normally kept closed by a safety valve which may be of various constructions, and is shown and described in the copending application, Ser. No. 717,348, filed March 26, 1934, but for which no special patent protection is claimed here. These valves substantially comprise an annular soft rubber gasket 63 which covers the gas holes 62, a mushroom-like lid 64 which is clamped over said gasket, and a saddle-shaped clasp 65 which is resiliently clamped against the inner side of the raised head 61 and coupled to the center of the lid by means of a rivet 66. The resilient cushion of the clasp consists of a soft rubber ring 67. When there is surplus gas pressure in the condenser, the gasket 63 together with the lid 64 is raised against the resiliency of rubber ring 67 to let the gas escape from under the gasket 63.

A modification of the venting device, which is likewise claimed and more fully described in said separate copending application, is shown in Fig. 5. In this case the dished end member 37 is recessed in the middle and spun inwardly to form a funnel-like nozzle 37a in which the vent holes 37b are provided. A rubber valve body 38 plugs up the central funnel mouth of the nozzle, and its flared out upper flange 38a resiliently covers the vent holes 37b. The gas releasing function of this device is analogous to the one above described.

The novel and peculiar construction of the anode member 22 is now to be described.

As already said, it consists substantially of a film-forming aluminum sheet, rolled into a spiral. For the sake of clearness only a small number of convolutions is shown in Figures 1, 2, and 3, and also the thicknesses of the conducting as well as the insulating sheets are shown greatly exaggerated. It is to be understood that actually the condensers will be of much smaller size and the spirals will be more closely wound. In order to facilitate the circulation of the electrolyte the aluminum sheet is perforated in any desired way as shown at 40 in Fig. 6. A further improvement for the same purpose which also provides an easier ascension of the gas bubbles in the axial zone of the condenser and thereby starts a tendency of the warmer liquid to circulate by rising through the middle, and descending at the periphery, as the arrows in Fig. 1 indicate, lies in the feature that, contrary to other spiral-wound condensers, the solid rod to which the inner end of the aluminum is usually attached along its edge in flag-like fashion, is omitted in this construction. Only at the lower edge, as shown in Fig. 6, a short stub 41 of the terminal 23 is fixedly attached to the anode sheet 22, by inserting the latter into a diametral slot of the terminal. Under the shoulder 24 an insulating washer 39 is

seated. Its main function is to guard the anode element against any short circuit which may otherwise be gradually built up between the bottom of the container and the lower edge of the spiral by sediments from electrolytic action.

The shank 42 of the terminal underneath the shoulder is tapered, principally to strengthen the hermetical sealing between the tubular neck 28 and the insulating sleeve 31 when the outer nut 44, threaded on the reduced end 43 of the terminal 23, is tightened, also to prevent an upward dislocation of the insulating substance by frictional stress exerted by the shank 42, if the nut is loosened and the condenser may be turned upside down. A washer 45 is inserted between the nut 44 and the swaged over flange 30 of the neck 28.

To provide insulating means between the separate turns of the spirally wound electrode or between the last outer turn and the container wall 20 which does not interfere with the free circulation of the electrolytic liquid, I have found a porous, i. e. loosely woven fabric best suited. The material may be linen, silk, cotton or the like and the preferred form in which said material is made, 25 is coarse gauze, offering the least total resistance and yet enough stiffness, not to collapse when wet. The latter quality can be improved and lightened by impregnating the gauze with a medium which not only waterproofs it but also protects the fiber 30 against the attack of whatever electrolyte may be used. Common glue or starch with which the commercial grade of gauze is sometimes impregnated, dissolves in borax solution—which is the most commonly used electrolyte—and other elec- 35 trolytes like sulphuric acid which sometimes is used,—especially when the anode is made of tantalum instead of aluminum—would attack the fiber itself. Rubberizing the gauze, however, or impregnating it with a suitable lacquer, i. e. with 40 celluloid dissolved in acetone or amyl-acetate will make it waterproof, as well as resistive to practically any of the well-known electrolytes, at the same time increasing its stiffness and dielectric strength without impairing its porosity.

The insulating gauze 46 may be combined with the metallic spiral 22 in two different ways. It may start with and be fixedly attached to the latter at the inner edge of the spirally wound sheet, which is creased at a sharp angle at 47 all the way up to the top of the anode element, as indicated in Fig. 2. In this way it covers the total area of the metal sheet and in addition it protrudes at the outer end, at A, so far that it can be wound around the outside of the spiral 55 roll for more than a whole turn to insulate it against the container wall. Furthermore, the gauze should be of somewhat greater width than the aluminum sheet so as to guard the edges of the spiral roll against any short circuit by sparking over from the cathode or by accidental contact of the inner turns with each other, while the water level of the electrolyte solution should be kept even higher than the top rim of the gauze. 60

Considering the natural tendency of any spiral 65 spring which is fastened at the inner end and confined within a circular or cylindrical space, to expand its turns the more they get away from the center which widens the spacing between the inner turns and narrows it between the outer 70 turns, it will be found superfluous to insulate the turns of smaller diameter from each other and it will be found sufficient if the insulating gauze is inserted between the outer turns only, as indicated in Fig. 3. The insulation between the last 75

anode spiral turn and the container, however, should preferably consist of a double layer of insulating gauze as shown in the same view.

As Figures 7 and 8 illustrate, means may be provided to secure the upper ends of the insulating sheets and the corners of the anode spiral respectively in place. At A the extreme outer corner of the aluminum sheet is creased over by what is usually called a "dog's ear", as at 10 50, Fig. 7. This is passed through a slot in the gauze and clipped over so as to clamp the gauze tightly to the metal. Fig. 8 shows a modification adapted to clamp the end of the gauze sheet to the edge of the aluminum sheet, which continues, 15 as is the case at point B, Fig. 3. A small rectangular incision is made in the edge of the metal sheet so that a little square clip 51 can be bent sideways and creased over the edge of the gauze, clamping the two sheets securely together.

20 Finally the whole spiral roll, comprising the aluminum sheet and the insulating gauze may be bound together by two annular bands 27, preferably of soft rubber.

It will be evident that the fine gas bubbles 25 which originate due to electrolytic action, are liable to get enmeshed and arrested by the netting of the gauze whereby they lose at least a part of their electric charge before they coagulate into bigger bubbles which will float upwardly. At 30 the same time the gauze netting will provide an efficient arrester of gas bubbles coming from the anode and attracted by the opposite polarity of the cathode wall.

It is obvious from the described construction 35 that not only the film-forming on the cathode, due to the causes explained, is effectively obviated but also the other objects listed are obtained.

In accordance with the provisions of the patent statute, I have described my invention, but I desire it is understood that it is not confined to the particular form shown and described, the same being merely illustrative, and that the invention may be carried out in other ways without departing from the spirit of my invention, 10 and therefore I claim broadly the right to employ all equivalent instrumentalities coming within the scope of the appended claims, and by means of which, objects of my invention are attained and new results accomplished, as it is obvious that the particular embodiments herein shown and described are only some of many that can be employed to attain these objects and accomplish these results.

Having now described my invention, what I claim as new, and desire to secure by Letters Patent, is:

1. In an electrolytic condenser, the combination with a container for a liquid electrolyte and 60 adapted to serve as cathode electrode and a loosely wound film-forming metal sheet, insulatingly supported within said container and serving as anode electrode; of a wide meshed non-conducting fabric sheet, inter-leaved between the spiral turns of the anode sheet and also between the last outer turn and the inside of the cathode-forming container, said fabric sheet being of such a width as to exceed the width of the anode sheet, measured parallel to the spiral axis.

70 2. In a condenser employing a liquid electrolyte comprising a spiral-wound film-forming anode and a metallic container serving as cathode,

means to intercept the gas bubbles generated by the electrolytic action and to neutralize their electrical charge by mechanical contact, said means comprising a wide meshed fabric sheet, interleaved between the outer turn of the spiral 5 anode and the metallic container.

3. In a condenser employing a liquid electrolyte, comprising an aluminum anode and an aluminum container serving as cathode, means to intercept the gas bubbles generated by electrolytic action 10 near the anode and to prevent them from forming a film on the cathode, said means comprising a non-conducting gauze mantle, surrounding said aluminum anode.

4. In a condenser, employing a liquid electrolyte and comprising an aluminum anode and an aluminum container serving as cathode, means to intercept the gas bubbles generated by electrolytic action near the anode and to prevent them from forming a film on the cathode, said means 20 comprising a non-conducting gauze mantle, surrounding said aluminum anode, said gauze impregnated with an agent insoluble in the electrolyte.

5. In a condenser, employing a liquid electrolyte and comprising an aluminum anode and an aluminum container serving as cathode, means to intercept the gas bubbles generated by electrolytic action near the anode and to prevent them 25 from forming a film on the cathode, said means comprising a non-conducting gauze mantle, surrounding said aluminum anode, and means to fixedly suspend said gauze mantle from the aluminum anode.

6. In an electrolytic condenser, comprising a 35 spiral-wound anode, consisting of a perforated aluminum sheet and an aluminum container for a liquid electrolyte serving as cathode, means to insulate the anode from the cathode and to prevent gas bubbles generated by electrolytic action 40 at the anode from forming a film on the cathode, said means comprising a non-conducting gauze mantle, interposed between the spiral roll of the anode and the cathode container.

7. In an electrolytic condenser, comprising a 45 spiral-wound anode, consisting of aluminum and an aluminum container for a liquid electrolyte, serving as cathode, means to intercept the gas bubbles generated by electrolytic action and to neutralize their charge by mechanical contact, 50 said means comprising a non-conducting gauze sheet, superimposed upon the spirally wound anode, interleaved between the separate turns and surrounding the last turn, so as to securely insulate the anode from the cathode container.

8. An electrolytic condenser consisting of an outer metallic container, serving as cathode and a film-forming anode, insulatingly suspended in a liquid electrolyte within the container, said condenser adapted to permit free circulation of the electrolyte upwardly through the middle and downwardly at the inner wall of the container with a free radial passage between these two courses, and comprising a perforated anode sheet, 60 loosely folded together to substantially occupy the space within the container, leaving a free central space, and an insulating gauze fabric, suspended between the folds of the anode sheet, and also between the latter and the inside of the container.

JOSEPH A. POITRAS.
